No. 13347

OCT. 24, 1882

UNITED STATES PATENT OFFICE.

JOHN GLEN, OF BROOKLYN, NEW YORK.

DESIGN FOR A PRINTED FABRIC.

SPECIFICATION forming part of Design No. 13,347, dated October 24, 1882.

Application filed September 26, 1882. Term of patent 3½ years.

To all whom it may concern:

Be it known that I, JOHN GLEN, of Brooklyn, Kings county, in the State of New York, have invented a new and original Design for Printed Fabrics; and I do hereby declare that the following specification, taken in connection with the accompanying illustration, forming a part of the same, is a full, clear, and exact description thereof.

My design relates particularly to printed fabrics known as "calicoes," although it is equally applicable to silks, woolens, and other fabrics, either printed or woven.

It consists in the representation of groups of flowers and flowering sprays, as will hereinafter appear.

Referring to the illustration, A represents a group of flowers, from which leaves *a* project, although these leaves may be omitted, if desired. Flowering sprays B are combined with the groups of flowers A. Groups of flowers A, with or without the leaves *a*, may be repeated upon the ground of the fabric to form the pattern, or the groups of flowers com-

bined with the flowering sprays B may be repeated to form the pattern.

The fabric may be produced in any preferred variety or combination of colors to give a desirable effect to the design.

What I claim, and desire to secure by Letters Patent, is—

1. The design for printed and other fabrics, consisting of groups of flowers A, substantially as set forth.
2. The design for printed and other fabrics, consisting of groups of flowers A and leaves *a*, substantially as set forth.
3. The design for printed and other fabrics, consisting of groups of flowers A and flowering sprays B, substantially as set forth.
4. The design for printed and other fabrics, consisting of groups of flowers A, leaves *a*, and flowering sprays B, substantially as described and shown.

JOHN GLEN.
